INTERLOCKING FLEXIBLE SHINGLE

Marston Lovell Hamlin, Lynbrook, N. Y., assignor to The Barrett Company, New York, N. Y., a corporation of New Jersey

Application December 9, 1931, Serial No. 579,885

19 Claims. (Cl. 108—7)

This invention relates to roofing and siding elements and more particularly to shingles of the interlocking type.

It is an object of my invention to provide a shingle of the interlocking type wherein a series of interlocking projections defined by slits or slots are formed within the border edges of the shingle near the lower corners thereof. The projections of the shingles interlock or lace with projections of other like shingles when laid in courses so that in each course a continuous interlocked lower edge to the weather is presented; the exposed portions of each shingle are thus secured against being lifted by the wind or otherwise displaced, and effective protection is thereby afforded against roof leakage with reduced headlap.

Other objects and advantages of my invention will appear from the following detailed description in which:

Fig. 1 represents a plan of a shingle embodying the principles of my invention wherein two interior projections are provided, each adjacent one transverse side edge of the shingle;

Fig. 2 is a plan of a portion of a roof or other supporting structure depicting the shingles laid in overlapping courses and in interlocking relation to provide a continuous interlocked lower edge in each course of shingles;

Fig. 3 represents in plan a modified form of the shingle of Fig. 1 wherein a recess is provided at the lower left-hand corner thereof in contradistinction to the projection formed in the corresponding portion of the shingle of Fig. 1;

Fig. 4 illustrates the interlock between the lower exposed edges of adjacent shingles of the type shown in Fig. 3;

Fig. 5 is a plan of a further modified shingle embodying the principles of this invention;

Fig. 6 illustrates the interlock between the lower exposed edges of adjacent shingles of the type shown in Fig. 5;

Fig. 7 represents in plan a modified form of the shingle of Fig. 5, the modification involving the removal of the lower left-hand corner of the shingle of Fig. 5 to provide a recess as shown;

Fig. 8 illustrates the interlock between the lower exposed edges of adjacent shingles of the type shown in Fig. 7;

Fig. 9 is a plan of a shingle somewhat analogous to the shingle of Fig. 1, differing therefrom chiefly in that the projections formed in the lower forward edge of the shingle extend inwardly toward the body portion of the shingle and not outwardly toward the transverse side edges thereof;

Fig. 10 represents the interlock between the lower exposed edges of adjacent shingles of the type shown in Fig. 9;

Fig. 11 represents a plan of a modified form of shingle embodying the principles of this invention;

Fig. 12 illustrates the interlock between the lower exposed edge of adjacent shingles of the type shown in Fig. 11;

Fig. 13 represents a still further modified form of shingle wherein the projections formed are of triangular shape and the lines of direction of the slits defining the projections, while at right angles to each other, are at acute angles to the forward edge of the shingles;

Fig. 14 shows the shingles of Fig. 13 laid to provide a continuous interlocked lower edge between the adjacent shingles of each course;

Fig. 15 is a plan of a modified form of the shingle embodying the principles of my invention wherein the projections at opposite transverse side edges of the shingle are of different shapes;

Fig. 16 shows the interlock between the lower exposed edges of adjacent shingles of the type shown in Fig. 15;

Fig. 17 is a plan of a further modification of the shingle of my invention wherein the oppositely disposed projections are of different shapes;

Fig. 18 shows fragments of two shingles of the type shown in Fig. 17 in interlocked relation;

Fig. 19 represents a plan of a further modification embodying the principles of my invention; and

Fig. 20 illustrates the interlock obtained between adjacent shingles of the type shown in Fig. 19.

With reference to Fig. 1, the reference numeral 20 designates a shingle of general rectangular shape defined by longitudinal edges 21 and 22 and transverse edges 23 and 24. A slot or slit 25 is formed in the forward longitudinal edge 22 of the shingle 20, preferably at right angles thereto and parallel to the adjacent side edge 23. An interior slit 26 is provided within the body of the shingle 20, preferably parallel to the forward longitudinal edge 22 and at right angles to the adjacent side edge 23, the slit 26 extending from a point adjacent the inner end of slit 25 a short distance toward the interior body portion of the shingle 20 and away from the adjacent side edge 23. Slits 27 and 28 are formed adjacent the opposite side edge 24 in a manner similar to the formation of slits 25 and 26, except that slit 28 extends in a direction opposite to the direction of slit 26.

It will be noted that by this method of slitting, two projections 29 and 31 are formed in the forward longitudinal edge 22 of the shingle 20, slits 25 and 26 and slits 27 and 28 being associated 5 with the projections 29 and 31, respectively.

The shingle of Fig. 1 is adapted to be laid in overlapping relation with like shingles in overlapping courses upon a roof or other supporting structure, as shown in Fig. 2. In laying, the 10 non-homologous side edges of each shingle are overlapped, i. e., the side edge 24 of a shingle A in Fig. 2 is lapped over a side edge 23 of an adjacent shingle B, which is first nailed, preferably 15 in the lower right hand corner as indicated by the reference numeral 30. This nail passes through the upper edge of the underlying shingle C and is covered by the lower left hand corner of shingle A. The projection 31 of shingle A is flexed inwardly and the projection 29 of shingle 20 B is flexed or bent outwardly, shingle A being moved to the left with respect to the already laid shingle B with projection 31 sliding through slit 25 of shingle B to effect the interlock. The projection 31 of shingle A engages the slit 25 of shingle B and the projection 29 of shingle B engages the slit 27 of shingle A, the projection 29 of the shingle B and the slit 27 of shingle A being exposed to view and the projection 31 of shingle A and the slit 25 of shingle B being cov- 30 ered.

It will be noted that the interlocking projections 29 and 31 are spaced from their respective side edges 23 and 24 approximately equal distances. Such spacing is preferable since when 35 adjacent shingles are interlocked, as for instance shingles A and B of Fig. 2, the locking joint formed by the projections 31 and 29 of shingles A and B, respectively, will lie at a point approximately midway between the overlapping side 40 edges 24 and 23 of the shingles A and B, respectively. This positioning of the joint insures its protection against the elements and seals the edges thereof against the entrance of moisture. By this method of interlocking adjacent shingles 45 in courses, the forward longitudinal edges of each shingle are locked down securely upon the roof or other supporting structure and constitute a continuous interlocked lower edge for each course of shingles which prevents warping of the individual elements and resists the action of wind and rain tending to work under the forward exposed edges of the shingles.

In Fig. 3, I have shown a modified form of the shingle of Fig. 1, the portion of the shingle which 55 is located between slit 27 and the adjacent side edge 24 being removed to form a recess 32. The shingle in Fig. 3 is laid in the same manner as disclosed in connection with the shingle of Fig. 1, except that the aforesaid portion of shingle 60 28 between the slit 27 and the adjacent side edge 24 is not exposed to view by reason of the substitution of the recess 32 therefor. For instance, as shown in Fig. 4, the projection 29 of one shingle 65 is bent outwardly and the projection 31 of an adjacent overlying shingle is bent inwardly, the projection 31 of the second shingle passing through the slit 25 of the first mentioned shingle, the projection 29 of the first shingle engaging the projection 31 of the second shingle upon 70 its upper face. This shingle may be employed where it is undesirable as a matter of general appearance to have the short projections defined between the slits 27 and the adjacent side edges 75 24 exposed to view along the lower edges of the

shingle courses, the recesses 32 being substituted therefor.

The shingle of Fig. 5, while generally resembling the shingles shown in Figs. 1 and 3, differs therefrom in the shape and size of the locking 5 projections and associated slits. A slit 33 is formed in the forward edge 36 of the shingle, preferably at right angles to said edge and parallel to, but spaced from, the transverse side edge 35. An interior slit 34 is provided within the 10 body portion of the shingle beginning at the inner end of slit 33 and extending therefrom at an acute angle to slit 33 toward the forward longitudinal edge 36 and the opposite side edge 39 of the shingle, terminating at a point spaced from 15 the forward longitudinal edge 36. A slit 37 is formed in the forward longitudinal edge 36, preferably at right angles thereto, and spaced from and parallel to the adjacent side edge 39. At the inner end of slit 37, a short interior slit 38 20 is formed within the body portion of the shingle extending toward the opposite side edge 35 at an obtuse angle to the line of direction of slit 37. Thus a projection 41 of a length greater than the length of a projection 42, but of the 25 same width, is formed.

In laying the shingle shown in Fig. 5, the side edges 35 and 39 of adjacent shingles are overlapped and the projection 42 of one shingle bent inwardly and passed under the projection 41 of 30 an adjacent underlying shingle. This locking arrangement provides a rigid and secure joint, the formation of which is facilitated by the shape of projections 41 and 42, i. e., by reason of pointed 35 upper portion of projection 41, it may more easily and quickly be passed through the slit 37 of the adjacent underlying shingle, and due to reduced end portion of projection 42, it may be readily passed under projection 41.

The shingle of Fig. 7 closely resembles that of 40 Fig. 5, with the exception that an additional slit 43 is made along a line parallel to the forward longitudinal edge 45 and extending to the adjacent side edge 46 to form a recess 44 at the lower left-hand corner of the shingle adjacent the 45 projection 47. A projection 48 is provided in the forward longitudinal edge 45, similar to the projection 41 of the shingle of Fig. 5. In laying, as shown in Fig. 8, the joint between adjacent shingles is formed by bending the projection 47 of 50 one shingle inwardly and passing it through slit 49 of the adjacent shingle, the projection 48 of the adjacent shingle engaging the outer face of the projection 47 of the first-mentioned shingle. When a series of shingles of this type are 55 thus locked to form a course of shingles, the lower edge of the course constitutes a continuous lower edge which is highly resistant to the entrance of wind and rain.

In Fig. 9, I have shown a still further form of 60 shingle embodying the principles of my invention. This shingle is in many respects similar to the shingle of Fig. 1, with the exception that the projections extend inwardly toward the interior of the shingle instead of outwardly toward the 65 side edges thereof, as in the shingle of Fig. 1. Slits 51 and 52 are formed in the forward longitudinal edge 55 of the shingle, preferably at right angles thereto. At their inner ends, slits 51 and 52 are extended toward the adjacent side edges 70 57 and 58, respectively, by means of slits 54 and 53, preferably formed parallel to the forward longitudinal edge 55. Thus, projections 58 and 59 are formed extending inwardly from points spaced from the side edges of the shingle toward 75

the interior of the body portion thereof. Slits 51 and 52 are associated with the projections 59 and 58 respectively.

Fig. 10 depicts adjacent shingles of the type shown in Fig. 9, laid in interlocking relation to secure a rigid and firm joint between adjacent shingles. Side edge 57 of one shingle is lapped over the non-homologous side edge 56 of an adjacent shingle, the projection 59 of the first shingle being bent inwardly and passed through the slit 52 of the adjacent shingle and the projection 58 of the adjacent shingle being bent outwardly and passed through the slit 51 of the first-mentioned shingle, the overlying shingles being moved to the right with respect to the underlying shingle to lock the elements. This arrangement insures a secure joint which provides a continuous interlocked lower edge when a course of shingles of this type are laid as described.

The shingle shown in Fig. 11 closely resembles the shingle of Fig. 9 with the exception that slits 61 and 62, formed at the inner ends of slits 63 and 64, respectively, lie at an obtuse angle thereto instead of at a right angle as with the corresponding slits 54 and 53 of the shingle of Fig. 9. Projections 65 and 66 thus formed are adapted to be locked with their corresponding slits 63 and 64 as shown in Fig. 12. The projection 65 of one shingle is bent inwardly to engage the slit 64 of an adjacent shingle and the projection 66 of the adjacent shingle is bent outwardly to engage the slit 63 of the first-mentioned shingle, thus providing a rigid interlock between adjacent shingles, whereby the forward longitudinal edges thereof are secured against warping and the action of wind in tending to raise the butt edges thereof.

The slits formed in the forward longitudinal edge of my shingle may lie at an acute angle to said forward edge, as shown in the shingle of Fig. 13, wherein two slits 67 and 68 are provided in the forward longitudinal edge of the shingle. The slits 67 and 68 are extended at right angles to their original line of direction along the lines of slits 69 and 71, respectively, toward the adjacent side edges of the shingle to form projections 72 and 73 of triangular shape with their free vertices pointed toward each other and away from the adjacent side edges of the shingle. In locking adjacent shingles of this type, a projection 73 of one shingle is bent inwardly and passed through the intersecting slits 67 and 69 of the adjacent shingle, the projection 72 of the adjacent shingle being bent outwardly and passed through the slits 68 and 71 of the first-mentioned shingle, as shown in Fig. 14.

In the modified form of shingle illustrated in Fig. 15, two slits 74 and 75 are formed in the forward longitudinal edge of the shingle adjacent to the opposite side edges thereof and preferably at right angles thereto, the slit 75 being shorter than the slit 74. At the inner end of slit 74, the longer slit, a slit 76 is formed in the interior of the shingle at an acute angle to the slit 74 and extending toward the adjacent side edge of the shingle, the two slits 74 and 76 thus defining a projection 78 which has a pointed upper end. At the inner end of slit 75, the shorter slit, an interior slit 77 is provided in the body portion of the shingle leading from the inner end of slit 75 at an obtuse angle thereto toward the adjacent side edge of the shingle, the two slits 75 and 77 defining a projection 79 having an oblique upper portion. In locking shingles of this type, the side edges thereof are overlapped with the

projection 79 being bent inwardly to engage and pass through the slit 74 of an adjacent shingle and the pointed projection 78 of the adjacent shingle being bent outwardly to pass through slits 75 and 77 of the first-mentioned shingle, as shown in Fig. 16.

In Fig. 17, a type of interlocking shingle embodying the principles of my invention is illustrated, this type of shingle having one locking projection thereof of relatively large size as compared with the other locking projection. With specific reference to the figure, a projection 81 is formed in the forward longitudinal edge 88 of the shingle adjacent a side edge 89 thereof by slit 82 entering the forward longitudinal edge 88 at an acute angle thereto and being extended at its inner end along a line 83 toward the adjacent side edge 89. Adjacent to and spaced from the opposite side edge 91, a projection 84 is defined by a slit 85 entering the forward longitudinal edge 88 of the shingle at an acute angle thereto, an interior slit 86 provided in the body portion of the shingle and extending in a direction parallel to the adjacent side edge 91 and an interior slit 87 in the body portion of the shingle parallel to the slit 85 and extending toward the adjacent side edge 91.

In locking shingles of this type, the non-homologous side edges 89 and 91 of adjacent shingles are overlapped, as shown in Fig. 18. The small projection 81 of one shingle is bent inwardly and passed through the slits 85 and 86 of an adjacent shingle, the larger projection 84 of the adjacent shingle being bent outwardly and passed through the slits 82 and 83 of the first-mentioned shingle.

Fig. 19 illustrates a further form of shingle provided with locking projections and slits in accordance with my invention. Slits 92 and 93 are provided leading into the forward edge 96 of the shingle at an acute angle thereto. Interior slits 94 and 95 are provided in the interior body portion of the shingle and are formed in a direction extending from the inner ends of the slits 92 and 93, respectively, toward the adjacent side edges but terminating at points spaced therefrom to define pointed projections 97 and 98, respectively. In laying this type of shingle in locked relation with an adjacent shingle of like type, the side edges are overlapped as shown in Fig. 20, the projection 97 of one shingle being bent inwardly and passed through the slit 93 of an adjacent shingle, the projection 98 of the adjacent shingle being bent outwardly and passed through the slit 92 of the first-mentioned shingle.

It will be noted that in all the above described shingles which embody the principles of the present invention, the spacing of each interlocking projection of each shingle from its adjacent side edge is such that when adjacent shingles are interlocked, the locking joint per se will be located at a point approximately midway between the overlapping side edges of the adjacent shingles. This position of the locking joint affords the maximum protection of the joint against the action of the elements since the portions of the shingles between the joint and the side edges will act to seal the joint against the entrance of moisture and the like.

The shingles of my invention may be composed of various materials, but they are preferably formed from a felt or fibrous base, saturated or otherwise impregnated with bituminous material to render it waterproof, coated with a bituminous composition, and subsequently surfaced with

granular material. The fibrous base is preferably manufactured in the shape of a long continuous web having parallel sides and of a width equal to the width of a number of shingles from which the shingles of the present invention may be cut without waste.

The shingles of this invention may be made in various colors or in one color, or the shingles may be surfaced partly with material of one color and partly with material of another color, thus providing a pleasing vari-colored effect when laid.

It will be further noted that nailing of the shingles in courses at the points indicated on Fig. 2 results in secure fastening of the shingles to the roof deck, utilizing but one nail for each shingle. This nail passes through the lower right corner of the shingle and also through the upper edge of the underlying element. Hence, the lower right corner of each shingle and the upper edge of an underlying shingle are secured in position by one and the same nail. The lower left corner is locked down by the interlock between the interlocking means in the overlapping corners of contiguous elements in the same course hereinabove described.

From the above description, it is evident that my shingle is possessed of many advantages. Projecting tongues, keys, appendages, and the like, depending from the body portion of the shingle are done away with, the interlocking of adjacent shingles being secured by a series of simple interlocking projections located near the lower corners within the border of the shingle. The resultant shingles, when laid in locked relation, form a series of courses of shingles, the lower edges of which are securely locked to the roof or supporting surface and form a rigid and unitary structure possessed of highly weather-resistant properties. Furthermore, the shingles may readily be applied and laid from either left to right or right to left, either interlocking projection of each shingle being adapted to lock with either of the interlocking projections of a contiguous shingle in the same course.

It is to be understood that this invention is not restricted to the present disclosure otherwise than defined by the appended claims.

I claim:

1. A flexible shingle adapted to be laid with other like shingles in overlapping courses, said shingle having in the neighborhood of the opposite lower corners thereof interlocking projections spaced from the sides of said shingle and defined by slits, the projection of one shingle being arranged to lock with the projection of an overlapping shingle in the same course and being so disposed that the forward edges of adjacent shingles occur in substantially the same straight line, the projections being spaced from the side edges a distance such that the interlocking projections of a pair of adjacent interlocked shingles lie approximately midway between the overlapping edges of said adjacent shingles.

2. A felt base shingle of the interlocking type, adapted to be laid with other like shingles in courses and provided with slits leading into the forward edge thereof in the neighborhood of the opposite transverse edges, interior slits formed within the body of said shingle leading into said first-mentioned slits at an angle thereto, each of said first-mentioned slits and its associated interior slit defining a projection located near the adjacent transverse edges and arranged to lock with the nonhomologous slit in the forward edge and the associated interior slit of an adjacent

shingle to form a continuous interlocking lower edge.

3. A felt base shingle of the interlocking type, adapted to be laid with other like shingles in courses and provided with slits leading into the forward edge adjacent opposite side edges, said slits being extended at an angle to their original line of direction toward the interior of the shingle and away from the adjacent side edges, each of said slits defining a projection arranged to lock with the non-homologous slit of an adjacent shingle to form a continuous interlocking lower edge.

4. A felt base shingle of the interlocking type, adapted to be laid with other like shingles in courses and provided with slits leading into the forward edge thereof adjacent opposite side edges, said slits being extended at right angles to their original line of direction toward the interior of the shingle and away from the adjacent side edges, each of said slits defining a projection arranged to lock with the non-homologous slit of an adjacent shingle to form a continuous interlocking lower edge.

5. A felt base shingle of the interlocking type, adapted to be laid with other like shingles in courses and provided with slits leading into the forward edge thereof at right angles thereto adjacent opposite side edges, said slits being extended at right angles to their original lines of direction toward the adjacent opposite side edges and away from the interior of the shingle, the slits of each shingle defining a projection arranged to lock with the non-homologous slit of an adjacent shingle in the same course to form a continuous interlocking lower edge.

6. A felt base shingle of the interlocking type, adapted to be laid with other like shingles in courses and provided with slits leading into the forward edge thereof adjacent opposite side edges at an acute angle thereto, said slits being extended at an angle to their original lines of direction and away from the interior of the shingle and toward the adjacent side edges, each slit defining a projection arranged to lock with the non-homologous slit of an adjacent shingle to form a continuous interlocking lower edge.

7. A felt base shingle of the interlocking type, adapted to be laid with other like shingles in courses and provided with slits leading into the forward edge thereof adjacent opposite side edges at an acute angle thereto, said slits being extended at right angles to their original lines of direction away from the interior of the shingle and toward the opposite side edges thereof, each slit defining a projection arranged to lock with the non-homologous slit of an adjacent shingle to form a continuous interlocking lower edge.

8. A felt base shingle of the interlocking type, adapted to be laid with other like shingles in courses and provided with slits leading into the forward edge thereof at obtuse angles thereto and adjacent opposite side edges, said slits being extended at angles to their original lines of direction away from the interior of the shingle and toward the opposite side edges, each slit defining a projection arranged to lock with the non-homologous slit of an adjacent shingle to form a continuous interlocking lower edge.

9. A felt base shingle of the interlocking type, adapted to be laid with other like shingles in courses and provided with slits leading into the forward edges thereof at an obtuse angle thereto and adjacent opposite side edges, said slits being extended in directions at an angle to their orig-

inal lines of direction toward the adjacent side edges and away from the interior of the shingle, each slit defining a projection arranged to lock with the non-homologous slit of an adjacent shingle to form a continuous interlocking lower edge.

10. A felt base shingle of the interlocking type, adapted to be laid with other like shingles in courses and provided with slits leading into the forward edge thereof at an oblique angle thereto adjacent opposite side edges, said slits being extended in directions at right angles to their original lines of direction toward the adjacent side edges and away from the interior of the shingle, each slit defining a projection arranged to lock with the non-homologous slit of an adjacent shingle to form a continuous interlocking lower edge.

11. A felt base shingle of the interlocking type, provided with projections defined by slits leading into the forward edge thereof located adjacent to the opposite edges, one of said projections being defined by a relatively short slit leading into the forward edge and having an extending slit at an angle thereto from the interior edge and the other of said projections being defined by a relatively long slit leading into the forward edge of said shingle having an extending slit from the interior edge thereof at an angle thereto.

30 12. A felt base shingle of the interlocking type, adapted to be laid with other like shingles in courses and provided with openings leading into the forward edge thereof adjacent the opposite side edges, a portion of each opening being extended away from the original line of direction of the opening towards another opening, each opening defining a projection arranged to lock with an adjacent shingle.

40 13. A rectangular felt base shingle of the interlocking type, adapted to be laid with other like shingles in courses and provided with openings leading into the forward edge thereof adjacent the opposite side edges, a portion of each opening being extended away from the original line of direction of the opening, each opening defining a projection arranged to cooperate with an opening and a projection of a like shingle to form a lock.

50 14. A flexible rectangular shingle of the interlocking type, adapted to be laid with other like shingles in courses and provided with slits leading into the forward edge in the neighborhood of the lower corners thereof, defining interlocking projections spaced from the transverse edges of said shingle, each of which is adapted to lock with a projection of a like shingle in the same course.

55 15. A flexible rectangular shingle of the interlocking type, adapted to be laid with other like shingles in courses with the transverse side edges of contiguous shingles in overlapping and underlapping relationship, and with the transverse side edges of each shingle adapted to optionally underlap or overlap the transverse side edges of the con-

tiguous shingles, each shingle being provided with slits leading into the forward edge in the neighborhood of the lower corners thereof defining interlocking projections, each of which is adapted to lock with a projection of a like shingle in the same course.

16. A covering unit of a form to be laid as an individual interlocking shingle having an edge to be exposed and side edges extending generally parallel to each other in a direction transverse to said edge to be exposed, said unit being provided with a pair of cuts in the body thereof respectively adjacent a side edge, each of said cuts having a portion extending generally parallel to said parallel side edges inwardly from said edge to be exposed, each of said cuts having a portion extending from the inner end of said parallel portions thereof and transversely thereto toward the inner part of the unit.

17. An individual interlocking shingle having two parallel side edges and an edge to be exposed extending generally transversely to said side edges, said shingle having a pair of slits in the body thereof extending inwardly from said edge to be exposed substantially parallel to said side edges, each of said slits lying between a side edge and the center line of the shingle parallel to said parallel edges, said shingle also having a pair of cuts in the body thereof extending transversely to said parallel cuts, each of said transverse cuts extending from a parallel cut in a direction toward the center line of the shingle.

18. An individual shingle of interlocking type and of flexible material having like-extending side edges and an edge to be exposed extending transversely to said side edges, said shingle having a pair of cuts intersecting and extending inwardly from said edge to be exposed and so placed with respect to said edge and to said side edges of the shingle as to provide a tongue at each end of said edge to be exposed extending to said edge to be exposed and generally in the direction of said side edges, each of said cuts also having the inner portion thereof extending transversely of the portion intersecting said edge to be exposed and in the direction toward the central portion of the shingle to provide a tongue extending transversely to and toward a side edge from the central portion of the shingle.

19. Surface covering comprising a plurality of flexible shingles of the interlocking type, each of said shingles comprising a body portion having a forward edge and side edges and provided with locking openings leading into the forward edge in the neighborhood of said side edges, said locking openings being extended at an angle to their original line of direction and defining interlocking projections, said shingles being laid in courses with their forward edges in alignment and a locking projection of each shingle interlocked with a contiguous lapping shingle of the same course.

MARSTON LOVELL HAMLIN.
